JOHN W. BREWER, OF MAGNA, UTAH

RAIL JOINT

Application filed December 10, 1929. Serial No. 413,013.

The invention relates to rail joints. It has for its principal objects the provision of an improved joint of the over-lapping type which eliminates the pounding characteristic of the standard butt joint in which the line of joinder is at right angles to the longitudinal center line of the rail. The purpose is to provide a joint of this type, (1) which can be made at a reasonable cost either by sawing, or by the use of dies at the mill, while the rail is red hot, (2) which has all the elements of strength and safety of the standard joint, (3) which can be used with standard angle or splice bars, (4) in which 10 weakening of the web due to longitudinal splitting of the web of the rail is avoided, (5) and in which a centralizing effect is secured, tending to keep the rail ends in alignment, while at the same time avoiding any tendency 15 of the wheel flanges to catch and ride up on the rail. One embodiment of the invention is illustrated in the accompanying drawings, wherein:

Figure 1 is a plan view of the joint without the angle or splice bars. Fig. 2 is a bottom plan view. Fig. 3 is a side elevation. And Fig. 4 is a section on the line IV—IV of Fig. 3, but with the splice or angle bars applied in order to show the type of bar preferably used.

Referring to the drawings, 1 and 2 are the ends of abutting rails. The two rail ends meet along the three lines 3, 4 and 5, the lines 3 and 4 forming approximately a 60 degree V whose apex lies just at the side of the web 6. The line 5 preferably departs about 20 degrees from a right angle with the longitudinal center line of the rails and this line of contact extends only through the rail heads. The one rail end is thus provided with a V-shaped recess into which the V-shaped wedge of the other rail end fits. The rail ends are secured together by any desired form of splice or angle bars 7, 7 preferably 40 of the cross section shown in Fig. 4, held by the usual bolts 8 extending through the holes 9, 9, two only of which are shown.

The ends of the rails may be easily brought to the V-shape shown by sawing along the lines 3, 4 and 5 or may be formed at the roll-

ing mill while the rails are red hot by the use of suitable dies.

The inside of the rails which the flanges of the wheels engage is the one having the cut 5, so that there is no more tendency of the 55 wheels to catch and ride up on the rails than is the case in the standard butt joint in which the cut or line of division is at right angles to the center line of the rails. The slight angle given the cut 5 tends to centralize the two 60 rails and also to prevent relative lateral movement between the rail ends, as such ends must necessarily move away from each other in an endwise direction in order to permit of such movement. When the ends are held, 65 therefore, by the splice bars, the rail ends are much more secure against relative lateral movement than is the case with the ordinary butt joint construction.

Since the contact between the ends of the 70 rails in the head follows the line 3, there is no opportunity for the wheels to pound as they pass from one rail end to the next, so that the wear and tear upon the rolling stock and rails is substantially reduced as compared with a standard rail joint. At the same time the tongue at 10 (Fig. 1) is unobjectionable, since it is on the outside of the rail where it is free from the action of the 75 wheel flanges, which would tend to catch on the tongue, if it were located on the inner side of the rail head.

The joint has somewhat greater strength 80 than the standard joint; can be made at only slightly greater cost; has an increased degree of safety as compared with the standard joint; and has substantially increased wearing qualities due to the lack of pounding present in the regular joint and to the fact 85 that the V-interlock, with its centralizing tendency, relieves the splice bars and bolts of a considerable degree of strain. Other advantages of the structure will be readily apparent to those skilled in the art. While the 90 angle between the lines 3 and 4 is preferably about 60 degrees and that between the lines 3 and 5 is about 90 degrees, it will be understood that the invention is not limited to these 95 particular angles as they may be varied with- 100

in reasonable limits and still give a joint having the utility heretofore pointed out.

What I claim is:

1. In a device of the class described, two abutting rails, one of which has a V-recess at its end with the side walls thereof upright, and with the apex of the V terminating at the inner side of the web of the rail, and the other of which has a wedge at its end fitting said recess, the heads of the two ends at the apex of the V on the inner sides of the rails having their contacting surfaces lying at an angle approaching a right angle with respect to the longitudinal center line of the rails.
- 15 2. In a device of the class described, two abutting rails, one of which has a V-recess at its end with the side walls thereof upright, and with the apex of the V terminating at the inner side of the web of the rail, and the other of which has a wedge at its end fitting said recess, the heads of the two ends at the apex of the V on the inner sides of the rails, having their contacting surfaces lying at an angle to the opposite side of the V-recess approximating a right angle.
- 20 3. In a device of the class described, two abutting rails, one of which has a V-recess at its end with the sides thereof upright and approaching each other at an angle of approximately 60 degrees and with the apex of the V terminating at the inner side of the web of the rail, and the other of which has a wedge at its end fitting said recess, the end of the wedge which terminates in the head of the rail lying at an angle approximating 70 degrees to the longitudinal center line of the rail and engaging a similarly inclined surface at the end of the V-recess.

In testimony whereof, I have hereunto subscribed my name this 30th day of November, 1929.

JOHN W. BREWER.
